UNITED STATES PATENT OFFICE.

FRED E. JUSTUS, OF EL PASO, TEXAS.

DIRECTION-INDICATOR.

1,183,648.

Specification of Letters Patent. Patented May 16, 1916.

Application filed December 9, 1915. Serial No. 65,898.

To all whom it may concern:

Be it known that I, FRED E. JUSTUS, a citizen of the United States, and a resident of El Paso, in the county of El Paso and 5 State of Texas, have invented a certain new and useful Improvement in Direction-Indicators, of which the following is a specification.

One of the principal objects of my invention is to provide an improved electrically operated direction indicator, in the nature of an arm pivotally mounted in a casing and operated by an electro-magnetically controlled lever whereby to be moved into 15 positions for indicating the directions in which the vehicle to which the device is applied, is about to move.

A further object of the invention is to provide an improved device of the class described which will be extremely simple, durable, efficient in operation, and inexpensive to manufacture.

With these and other objects in view which will become apparent as the description proceeds, the invention resides in the construction, combination, and arrangement of parts hereinafter more fully described and claimed and illustrated in the accompanying drawing in which like characters of reference indicate like parts throughout the several figures, of which—

Figure 1 represents a view in front elevation of a direction indicator constructed according to my invention. Fig. 2 represents 35 an enlarged elevational view thereof with the front plate of the device removed. Fig. 3 represents a view in section taken vertically and transversely on the plane indicated by the line 3—3 of Fig. 2.

40 The invention provides generally a casing on whose front plate a pointer is pivotally mounted, said pointer being controlled by a lever carrying a pin which extends through a slot in the front plate and engages in a slot in the pointer, said lever being mounted between electro-magnets controlled by circuits including switches mounted on the steering wheel of the machine or at some other convenient point.

50 Referring more particularly to the drawing, 5 indicates a casing generally, which

forms the top, bottom and side walls of the housing within which the indicator is mounted, said casing being provided with an inwardly extending flange 6 at its forward edge. The floor or back of the housing constitutes a plate 7 having a plurality of outturned ears 8 riveted or otherwise secured to the casing 5, said plate 7 being set within the rear portion thereof in the manner indicated in Fig. 3. Toward the forward portion of the housing, is arranged a partition 9 having a forwardly extending marginal flange 10 fitting within casing 5 and at its forward edge being arranged adjacent the flange 6. Between the front edge of flange 10 and the rear face of flange 6 is arranged a transparent pane 11. This pane is arranged in spaced relation with the partition 9. A pair of spacer plates 12 are 70 arranged adjacent the lateral edges of the plate 7, being secured thereto, and against these plates the partition 9 rests, being secured thereto in any suitable manner. A bracket 13 of suitable design may be secured to the lower portion of the casing 5, to serve as means whereby the housing may be suitably connected on the rear wall of the body of the automobile or other machine with which the device is to be used, or in 80 some other desirable place.

A pointer 14 is pivoted at its lower end upon a pin 15 carried by plate 9 near the lower portion of the latter, said pointer being provided adjacent its pivotal point 85 with a longitudinally extending slot 16 through which a stem or projection 17 carried at the lower end of an oscillatory lever 18 extends. The stem 17 also extends through a curved slot 19 provided in plate 90 9 where it may swing back and forth. Lever 18, as shown, is arranged between the partition 9 and plate 7, and at its upper end is pivotally connected with plate 7 upon an inwardly extending pin 20. The lever 18 95 adjacent its pivotal point, is provided with a pair of oppositely extending or diverging leaf springs 21. The lever 18 is mounted upon a plate 22 suitably secured to the rear wall or back 7 of the device. The outer ends 100 of the springs 21 rest against spaced pins 23 secured to plate 22, whereby the lever

18 will be normally retained in vertical position.

The lever 18 is controlled by two sets of electromagnets 24 mounted upon the plate 22 and at the sides of the lever, and which diverge toward the lower portion of the casing. One end of the winding of each magnet is grounded on the plate 22 as at 25, and the other end is connected with a binding post 26. From each post 26 extends a wire 27 and 28 respectively, to switches 29 and 30 respectively, these switches being connected by a wire 31 with one pole of a battery 32, and at the opposite pole of the battery a wire 33 connects with the binding post 34 carried on the plate 22.

When the switches are open the magnets are not energized, and the lever remains through the tension of springs 21 in a vertical position, thus retaining the pointer 14 in vertical position. If however the vehicle is to make a turn, say, to the right, the switch 30 will be closed, thus closing a circuit through the wire 31, switch 30, wire 28, binding post 26, to the right hand magnet, and back through the plate 22 and wire 33 to the battery, thus energizing the magnet and drawing the lever 18 against the tension of springs 21 toward the right. This will cause the shifting of the pointer 14 to the right hand side as indicated in Fig. 1, whereby to indicate to the drivers of following vehicles that a turn to the right is to be made. When the switch 30 is opened, the magnet will become de-magnetized and the lever 18 will again resume its normal position, thus moving the pointer back to the vertical. When the switch 29 is closed a similar action takes place with respect to the left hand magnet and the pointer is drawn toward the left until the switch is re-opened.

Mounted upon the upper portion of plate 7 is a socket 36 within which a light 37 is arranged. Any suitable arrangement whereby the light may become illuminated at will or when desired may be employed. The light 37 extends through an opening 38 provided in the partition 9 to be arranged with 50 in the chamber formed between the partition 9 and the pane 11, whereby to properly illuminate the pointer 14.

Although I have described the preferred embodiment of my invention, I may desire 55 to make such changes in the construction, combination, and arrangement of parts thereof, as do not depart from the spirit of the invention and the scope of the appended claims.

60 I claim:—

1. A device of the class described comprising an open ended casing having an inwardly extending flange at its forward end, a plate arranged within the rear end of the

casing and provided with ears adapted to 65 be connected to the casing for holding the plate in position, a partition arranged within the casing in advance of the plate, spacer plates arranged between said plate and partition for maintaining the latter in position, said partition being provided with a forwardly extending marginal flange, a transparent pane arranged between said marginal flange and the inwardly extending flange of the casing, a pointer pivotally 75 mounted adjacent its lower end upon the partition, said pointer being arranged between said partition and said transparent pane, and being provided near its pivotal point with a longitudinally extending slot, 80 a base plate arranged upon the first said plate within the casing, a lever pivotally connected with said base plate and depending therefrom, said lever having an outwardly bent portion extending through the 85 slot in the pointer and through an arcuate slot provided in the partition, a pair of leaf springs connected with the lever, pins against which the ends of the springs bear whereby to retain the lever normally in 90 vertical position, electro-magnets arranged upon the said base plate on each side of the lever, said magnets diverging from each other downwardly, and means whereby either of the magnets may be energized at 95 will for attracting the lever.

2. A device of the class described including a casing, a rear plate, a partition, and a transparent plate arranged within the casing in spaced relation to each other, a pointer pivotally connected upon the partition beneath the transparent plate, a lever pivoted within the casing beneath the partition, and being provided with an outwardly extending portion projecting through 105 a slot in the partition and into a slot provided longitudinally of the pointer, spring means carried by the lever for maintaining the latter normally in vertical position, an electro-magnet arranged on each side of the 110 lever, and means whereby either of the electro-magnets may be energized at will for drawing the lever in one direction or another whereby to shift said pointer into direction indicating positions. 115

3. A device of the class described including a casing, a pointer pivotally mounted thereon, a lever arranged within the casing and provided with a portion extending through a slot in the pointer, spring means 120 for normally maintaining the lever in vertical position whereby to maintain the pointer in neutral position, and electrically operated means for shifting the lever in one direction or another at will whereby to move 125 the pointer into direction indicating positions.

4. A direction indicator including a casing

having a pointer pivotally mounted thereon, means for illuminating the pointer, a lever arranged in the casing and having a portion engaging through a slot provided in the pointer, resilient means normally maintaining the lever in position for retaining the pointer in neutral position, and means for shifting the lever in one direction or another at will, whereby to shift the pointer into direction indicating positions.

5 FRED E. JUSTUS.
